UNITED STATES PATENT OFFICE.

MARVIN L. CHAPPELL AND MERLE M. MOORE, OF EL SEGUNDO, CALIFORNIA,
ASSIGNORS TO STANDARD OIL COMPANY OF CALIFORNIA, OF SAN FRANCISCO, CALIFORNIA, A CORPORATION OF CALIFORNIA.

PROCESS FOR CLARIFYING AND IMPROVING THE COLOR OF PETROLEUM OILS.

1,404,375.

Specification of Letters Patent. Patented Jan. 24, 1922.

Application filed February 18, 1920. Serial No. 359,756.

To all whom it may concern:

Be it known that we, MARVIN L. CHAPPELL and MERLE M. MOORE, citizens of the United States, residing at El Segundo, in the county 5 of Los Angeles and State of California, have invented a new and useful Process for Clarifying and Improving the Color of Petroleum Oils, (No. 2,) of which the following is a specification.

10 This invention relates to the art of clarifying and improving the color of petroleum oils by the use of clarifying and decolorizing agents. While not necessarily limited thereto, it more specifically refers to the art of 15 clarifying and improving the color of lubricating oils.

One object of the invention is to provide a method or process whereby a substantially uniform clarified oil of the desired color may 20 be produced with a minimum consumption of the clarifying and decolorizing agent; another object is to provide such a process which may be performed with a minimum consumption of time.

25 An object of the invention is to provide a process, for the purpose specified, whereby the oil to be treated and the clarifying and decolorizing agent may be thoroughly intermingled, in any suitable manner, and not 30 depend upon percolation of the oil through the agent.

An object of the invention is to provide a method whereby hydrocarbon oil may be mixed with a clarifying and decolorizing 35 agent and quickly heated to a temperature of 250° F., or higher, thoroughly commingled and cooled before any substantially oxidizing action can take place.

40 An object of the invention is to provide a method whereby a more finely comminuted decolorizing and clarifying agent may be used to clarify and decolorize a petroleum hydrocarbon oil than has heretofore been used.

45 An object of the invention is to provide a method or process whereby the treated oil may be quickly cooled and filtered without loss in color or the formation of oxidized products.

50 Another object of the invention is to provide a means whereby a hydrocarbon oil containing a small percentage of water, (for instance $\frac{1}{4}$ of 1% to 2%, approximately,) commingled with a clarifying and decolor-

izing agent, may be quickly or rapidly 55 heated in such manner as to drive off or convert all of said water into steam and to exclude substantially all of the air from said hydrocarbon oil, thereby substantially preventing any oxidizing action. 60

The extraction of coloring matter from petroleum oils is generally understood to be an adsorbing process, dependent upon time of contact, temperature and surface exposed. For example, for a given quantity and 65 weight the finer the comminution of the decolorizing agent, the more surface thereof will be exposed to the oil and the more coloring matter will be condensed or adsorbed upon the surface of the decolorizing agent. 70 We have found that a decolorizing agent, ground so that approximately 97% will pass through a 200 mesh sieve or screen, gives the more satisfactory results for our process or method. 75

Heretofore by usual methods it has been customary to clarify and improve the color of hydrocarbon oils and particularly lubricating oils by percolating such oil through long pipes or other forms of containers filled 80 with a decolorizing and clarifying agent, such decolorizing and clarifying agent comminuted or finely divided so it will pass through a No. 30 standard mesh sieve but will be retained on a No. 60 mesh standard 85 sieve; also when fullers' earth is used for the more viscous oils, the same has been used of such comminution as to pass through a 15 to 30 mesh sieve. In such processes the oil is usually retained at substantially 130° 90 F. These methods have been found very slow and usually require from 5 to 7 days before the oil percolates through the filtering bed thus formed. Not only have these methods used been found to be slow but 95 they also require the use of very large quantities of decolorizing agent. With such methods as heretofore practiced it has been noted that the viscosity of the treated oil has been substantially lowered. 100

With the usual methods of clarifying and decolorizing oils it has been customary to subject such oils to what is known as a brightening operation in which the water is removed from the oil. Ordinarily in this 105 brightening process air is employed and a percentage of oxygen is absorbed by the oil with the consequent formation of a percent-

age of oxidized products which interfere with the clarifying and decolorizing agent and in the separation thereof from the oil. By our improved process this oxidation is 5 avoided by treating the oil with a suitable decolorizing agent without first employing any such brightening process or removing the water content of the oil after the oil has been treated with acid, caustics or the 10 like.

By our process, in its preferred form, we mix the clarifying agent directly with the oil and do not depend upon mere percolation of the oil through such agent.

15 With our process as hereinafter described and explained we require only approximately 2 hours for the entire treatment of the oil for the purpose of decolorization and clarification and at the same time retain the oil 20 with a greater viscosity than where the usual methods or processes are used, and also are enabled to perform the clarification and decolorization with a minimum consumption of decolorizing and clarifying 25 agent.

By our process also we obtain a superior product and substantially free from oxidized products.

In the preferred embodiment of our invention our method or process in clarifying or improving the color of hydrocarbon oil 30 consists either in batch treatments or in a continuous method whereby hydrocarbon petroleum or lubricating oil is quickly heated 35 to a temperature between 250° F. and the temperature of the peak of the reaction of a clarifying and decolorizing agent, by means of suitable heating devices, and while such oil is commingled with such clarifying or 40 decolorizing agent, the latter in a finely comminuted or pulverized condition, and in such quantities as may be necessary to obtain the desired color or grade; continuing the commingling or agitating of such oil and de- 45 colorizing agent for such a period of time and at such a temperature as is necessary to obtain the desired extraction of color from said oil; continuously discharging the vaporized water in such manner that the vapor 50 substantially excludes the contact of air with the oil undergoing treatment; then immediately partially cooling said oil and said inter-mingled oil and agent to a temperature which substantially prevents oxidation, and 55 then separating from such oil the decolorizing agent and the adsorbed matter by suitable means; and finally cooling the resultant clarified oil to the desired temperature.

More specially our invention provides a 60 process whereby a hydrocarbon oil may be intimately commingled with a clarifying and decolorizing agent and quickly brought to the desired temperature for the reaction of the oil and agent by rapid circulation of 65 the inter-mingled oil and agent through a

suitable heater or chamber, without any part of such oil being heated beyond the desired temperature; thoroughly commingling the heated oil and decolorizing agent, discharging the vapor or steam resultant from the 70 water in the oil and utilizing the vapor or steam thus created to prevent oxidation of the oil; quickly partially cooling the same below oxidizing temperature so as to minimize the oxidation; separating the agent and 75 its adsorbed matter from the oil and then cooling the oil to the desired temperature.

The preferred embodiment of our invention will be more readily understood by reference to the accompanying drawings, illustrating a form of apparatus by which the same may be performed. The drawing is a diagrammatical form of an apparatus by 80 which such preferred embodiment of our invention may be performed.

In the drawings 2 represents a storage tank for the oil to be treated. This tank 2 is connected by a pipe 3 with a treating tank 4. The tank 4 may be entirely open at its top or may be closed by a dome 5 as indicated in the drawings and provided with a vapor outlet 6. The treating tank 4 is connected by means of a pipe 7 to a pump 8 which discharges through a pipe 9 connected through a valve 10 to a heater 11 and 95 through a valve 12 to a cooler 13. The heater 11 may be of any suitable form of construction but we prefer to use a Braun heater which is a heater composed of small pipes enclosed in a shell so that the heating medium fills the shell and surrounds the pipes through which the oil is conducted, thus affording a quick means of raising the temperature of the oil as it passes through the pipes or tubes of the heater. This heater 100 11 is connected by means of a pipe 14 to the treating tank 4. As shown in the drawings the heater 11 is also connected by a pipe 15 to the pump 8. 16 represents a valve in the pipe or line 15 and 17 represents a valve in 110 the pipe or line 7. 18 represents a storage and feeder bin or hopper in which the finely comminuted clarifying or decolorizing agent is provided. From this bin 18 such agent may be introduced into the treating tank 4 115 in the desired quantities, such quantities being regulated by means of a suitable slide or valve 19. 13 represents a cooler which is connected to receiver 21 by a suitable pipe 22. The receiver 21 may be connected to a 120 pump 23 by pipe 24. The pump 23 discharges through a pipe 25 which in turn is connected to a filter press, device or chamber 26 of any ordinary or preferred construction. 27 represents a receiving pan to hold 125 the spent clarifying and decolorizing agent. 28 represents a conveyor to convey the spent clarifying and decolorizing agent to storage or for recovery.

The filtering device or press 26 is con- 130

nected to a cooler 29 by a suitable pipe 30 and in turn the cooler 29 is suitably connected to a storage vessel 31 as by a pipe 32. 33 indicates a pipe which leads from the storage vessel 31 to any other suitable place or means of storage.

When the apparatus is in the form shown in the drawing the preferred embodiment of our process is performed as follows:

- 10 The treating tank 4 is first filled with the predetermined amount of hydrocarbon oil to be treated, such oil being drawn through the pipe 3 from the storage tank 2. This oil may contain approximately from $\frac{1}{4}$ of 1% 15 to approximately 2% of water. Decolorizing and clarifying agent in the required amount is then added by suitable operation of the valve 19. This decolorizing agent is thoroughly commingled with the oil by any 20 suitable means, such for instance, as circulation by means of a pump 8 through the heater 11 and back into the tank 4. This circulation is continued until the commingled decolorizing agent and oil is raised 25 to a temperature of approximately 250° F., depending upon the oil to be treated. While the commingled oil and agent are thus raised to a temperature between 250° F. and the temperature of the peak of the reaction 30 of the oil and agent, the water in the oil is vaporized or turned into steam and as the oil, agent and steam or vapor is discharged through the pipe 14 into the tank 4, this vapor or steam rises and is discharged 35 through the vapor outlet 5 at the top of the chamber 4 or through the open top of the chamber if a dome or cover is not used on the chamber. We have found that the conversion of this water into vapor or steam 40 and its rising from the body of oil so being treated with the agent substantially prevents oxidation and substantially excludes air from contact with the oil while being thus treated. It is thus seen that this vapor or 45 steam produced by the water in the oil excludes air from coming into contact with the oil while being treated, and also excludes or carries the air out of the oil. After the commingled oil and agent have thus been 50 raised to the desired temperature, they are subjected to this temperature for a predetermined period, which with certain oils does not exceed 5 minutes. By thus quickly raising the temperature of the commingled 55 oil and decolorizing agent and circulating the same through a suitable heating device, we are enabled to subject the commingled oil and agent to the critical temperature for the desired length of time without subjecting 60 any portion of the oil to a greater temperature than desired, thus minimizing the oxidation which would be promoted by too high a temperature and eliminating the danger of any portion of the oil approaching 65 decomposing temperature.
- After thus being subjected to the critical temperature for the desired length of time the commingled oil and agent are immediately passed through a suitable cooler, such as the cooler 13 indicated in the drawings. 70 In this cooler the temperature of the commingled oil and agent is reduced below the temperature of rapid oxidation and discharged into a suitable receiver 21 from which they are drawn by the pump 23 and 75 discharged through the filtering press or apparatus 26, where the clarifying agent with the adsorbed coloring matter is separated from the oil and discharged and the clarified and decolorized oil is discharged 80 into the cooler 29 from which cooler such oil may be passed to any suitable storage vessel such as the storage vessel 31.
- The passage of the commingled oil and agent through the heater 11 gradually but 85 very quickly heats the commingled oil and agent to the desired temperature without heating any material quantity of the oil beyond this temperature.
- The passage of the treated hydrocarbon oil 90 through the cooler 13 rapidly cools said oil to a temperature at which no material oxidation or material lowering in the color of the oil will occur upon standing. This temperature is regulated to conform to the filtering 95 rate of the oil. We prefer to maintain a slightly higher temperature during the filtration of oils which are of a heavy viscosity.
- While we prefer to use a filter press as 100 the means of separating the clarifying and decolorizing agent from the oil, our process is not necessarily limited thereto as we may use any suitable filtering means, centrifugal machine or other mechanical device by means of which the oil is obtained substantially free 105 from the spent clarifying and decolorizing agent.
- As a clarifying and decolorizing agent, we may use animal char, bone ash, fullers' earth, certain clays which have been treated with 110 acid, such as the clays from the well-known Death Valley, California, deposits, or any other ordinary or preferred material suitable therefor, and which will clarify and improve the color of hydrocarbon petroleum oil. 115
- In utilizing our process for clarifying and decolorizing certain lubricating oils derived from California crude oils, we have found that by quickly raising the temperature of the commingled oil and decolorizing agent 120 to approximately 300° F. and maintaining same at such temperature for approximately 5 minutes and then quickly cooling the same to approximately 150°, we secure the best results. It is obvious, therefore, that our 125 process is not limited specifically to a particular temperature, the range of temperature to which the commingled oil and agent shall be subjected being from substantially 250° F. to the heat or temperature at which 130

the peak of the reaction takes place. Best results are secured by the higher temperatures so long as the temperature of the commingled oil and agent is retained below 5 the temperature of the peak of reaction.

We claim:

1. The process of clarifying and improving the color of hydrocarbon petroleum oil which consists in commingling a hydrocarbon 10 oil containing water and a clarifying and decolorizing agent, quickly raising the same to the temperature of the decolorizing reaction, coincidently discharging the vaporized water to substantially exclude the contact of air with the oil undergoing treatment, maintaining such temperature to effect such reaction, and then separating the agent and adsorbed coloring matter from the oil.
2. The process of clarifying and improving the color of hydrocarbon petroleum oil which consists in quickly raising a commingled hydrocarbon oil containing water and a clarifying and decolorizing agent to the temperature of the decolorizing reaction, 20 the water present being volatilized and the resultant vapor utilized to substantially exclude the contact of air with the oil undergoing treatment, maintaining such temperature to effect such reaction, immediately 25 cooling the inter-mingled oil and agent to such a temperature as to prevent rapid oxidation, and then separating the agent and adsorbed coloring matter from the oil.
3. The process of clarifying and improving the color of a hydrocarbon petroleum oil which consists in commingling with the oil containing water a clarifying and decolorizing agent comminuted so that substantially 35 97% of such agent will pass through a 200 mesh sieve or screen, quickly raising the commingled oil and agent to a temperature not substantially less than 250° F. and below the peak of the decolorizing reaction, the water present being volatilized and the resultant vapor utilized to substantially 40 45 exclude the contact of air with the oil undergoing treatment, immediately cooling the same to substantially prevent oxidation, and separating the oil from the agent and adsorbed matter.

clude the contact of air with the oil undergoing treatment, maintaining such temperature until the reaction is effected, immediately cooling such oil and agent below the temperature of rapid oxidation, and separating the oil and agent with its adsorbed coloring matter.

4. The process of clarifying and improving the color of a hydrocarbon petroleum oil which consists in subjecting such oil containing water commingled with a finely divided clarifying and decolorizing agent to a temperature not substantially less than 250° F. and below the temperature of the peak of the decolorizing reaction, the water present being volatilized and the resultant vapor utilized to substantially exclude the contact of air with the oil undergoing treatment, maintaining such heat during the period of such reaction, immediately partially cooling the intermingled oil and agent below the temperature of rapid oxidation, and separating the oil and agent with its adsorbed coloring matter.

5. The process of clarifying and improving the color of a hydrocarbon petroleum oil which consists in rapidly circulating through a heating chamber the oil containing water and intimately commingled with a finely comminuted clarifying and decolorizing agent to cause the reaction of said oil and agent, the water present being volatilized and the resultant vapor utilized to substantially exclude the contact of air with the oil undergoing treatment, immediately cooling the same to substantially prevent oxidation, and separating the oil from the agent and adsorbed matter.

Signed at El Segundo, California, this 9th day of February, 1920.
